US00D875678S

(12) **United States Design Patent** (10) **Patent No.:** **US D875,678 S**
(45) **Date of Patent:** **** Feb. 18, 2020**

(54) **WIRELESS CHARGER**

(71) Applicant: **SAMSUNG ELECTRONICS CO., LTD.**, Suwon-si (KR)

(72) Inventors: **Jinwook Kim**, Yongin-si (KR); **Syeon Lee**, Eumseong-gun (KR)

(73) Assignee: **SAMSUNG ELECTRONICS CO., LTD.**, Gyeonggi-Do (KR)

(**) Term: **15 Years**

(21) Appl. No.: **29/675,148**

(22) Filed: **Dec. 28, 2018**

(30) **Foreign Application Priority Data**

Oct. 23, 2018 (KR) 30-2018-0048695

(51) **LOC (12) Cl.** **13-02**

CLAIM

The ornamental design for a wireless charger, as shown and described.

DESCRIPTION

FIG. 1 is a top perspective view of a wireless charger, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom perspective view thereof.

The broken lines illustrating portions of the wireless charger form no part of the claimed design.

1 Claim, 5 Drawing Sheets
